ICE CREAM CARTON HOLDER

Robert E. Bogart, Toledo, Ohio, assignor, by mesne assignments, to Roll Dippers, Inc., Maumee, Ohio, a corporation of Ohio

Filed June 19, 1961, Ser. No. 65,639

Term of patent 14 years

(Cl. D58—12)

The side and end of the ice cream carton holder which are not shown in FIGURE 1 are substantially the same as the side and end shown.

I claim:

The ornamental design for an ice cream carton holder, as shown and described.
